(57) CLAIM

The ornamental design for a fan shaped American flag light, as shown and described.

DESCRIPTION

FIG. 1 is a perspective view of a fan shaped American flag light, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an enlarged view of a portion indicated in FIG. 1;

FIG. 9 is an enlarged view of a portion indicated in FIG. 1;

FIG. 10 is an enlarged view of a portion indicated in FIG. 4;

FIG. 11 is an enlarged view of a portion indicated in FIG. 6; and,

FIG. 12 is an enlarged view of a portion indicated in FIG. 7.

The broken lines in the figures illustrate portions of the fan shaped American flag light that form no part of the claimed design.
